(57) **CLAIM**

The ornamental design for a notebook computer, as shown and described.

DESCRIPTION

FIG. 1 is a top perspective view of a notebook computer; FIG. 2 is a front view of the notebook computer of FIG. 1; FIG. 3 is a rear view of the notebook computer of FIG. 1; FIG. 4 is a left-side view of the notebook computer of FIG. 1; FIG. 5 is a right-side view of the notebook computer of FIG. 1;

FIG. 6 is a top plan view of the notebook computer of FIG. 1; FIG. 7 is a bottom plan view of the notebook computer of FIG. 1;

FIG. 8 is a top perspective view of the notebook computer without an example environment; and, FIG. 9 is a partial enlarged view of FIG. 1 that is included to more clearly depict the design feature on the top of the bottom portion of the notebook computer, as viewed from the top perspective view (a-a', b-b', c-c', d-d') of FIG. 1.

Features shown in broken lines in FIGS. 1, 2, 3, 4, 5, 6, 7, and 9, form no part of the claimed design.

The broken lines shown immediately surrounding the straight-line surface shading on the rear portion of the computer in FIG. 7 represent the bounds of the claimed design, while all other lines are directed to environment and form no part of the claimed design.
